E. R. JONES

EMBALMING ACCESSORY

Filed Oct. 20, 1924

UNITED STATES PATENT OFFICE.

EPHRAIM R. JONES, OF CORBIN, KENTUCKY.

EMBALMING ACCESSORY.

Application filed October 20, 1924. Serial No. 744,761.

To all whom it may concern:

Be it known that I, EPHRAIM R. JONES, a citizen of the United States, residing at Corbin, in the county of Whitley and State of Kentucky, have invented certain new and useful Improvements in Embalming Accessories, of which the following is a specification.

The invention generally relates to embalming accessories and has for its object to provide an improved construction of drain pan for use in facilitating the embalming function in a manner contributing considerably to the ease and efficiency of accomplishment thereof and insuring against undesirable soiling and destruction of carpets, rugs and the like by the spilling of fluid.

With the above and other objects in view that will hereinafter appear, the invention further resides in those novel details of construction, combination and arrangement of parts first fully described in the annexed specification, then particularly pointed out in the appended claims, reference being had to the accompanying drawing, in which:

Figure 1 is a perspective view showing the invention mounted for use.

Figure 2 is a central longitudinal section of the invention mounted for use.

Figure 3 is a side elevation of the invention illustrating its self-supporting feature.

Figure 4 is an enlarged fragmentary section taken on the line 4—4 on Figure 2, and,

Figure 5 is a detail cross section illustrating the manner in which an upholstered cushion may be removably substituted for the drain pan proper.

It is the common practice with embalmers, when operating on a body, to make an incision in the armpit, usually under the right arm and close to the body. The axillary vein is then raised and a drain tube inserted therein, a rubber tube being connected to the drain tube and to a blood bottle or other receptacle to take off and impound the blood.

Many difficulties arise in the carrying out of this procedure some of which are mentioned below and others of which will be obvious upon thought, and it is to provide a means, soon to be described in detail, for effectively overcoming such difficulties that I have addressed my efforts with signal success.

Often the blood will not flow as the arm

pit incision is made and the drain tube and rubber tube operatively inserted. The natural course then is to disconnect the rubber tube. It is a common experience to have the blood start to flow copiously just when most inconvenient, just after the tube has been disconnected. If preliminary precautions have not been taken rugs and carpet are sure to be soiled or even ruined.

The embalmer's labor is commonly carried on in private homes and to guard against emergencies as above outlined it is necessary to spread rubber sheeting or similar means over the floor to protect against such accidental "spillings."

Also, it frequently happens, during the embalming operation, that a body purges, i. e., blood or blood mixed with other fluid flows excessively from the mouth and nostrils. This fluid naturally runs down over the face of the corpse onto the embalming board, and if not properly restrained, onto the floor.

In addition to the above it is often necessary to wash and massage the face and shampoo the head. In cases of accident where the skin of the head and face is lacerated, excessive bleeding occurs and increases the difficulty of providing against "spillings."

In carrying out the ideas of my invention I provide a drain pan so constructed and adaptable to use as to be effective in receiving and confining the fluids exuding from the body and for providing for the proper carrying off of the fluid so confined. This device is removably mountable upon any approved type of embalming board, indicated in the drawing by the numeral 1, so as to be adaptable to use in the common way, illustrated in Figure 1 of the drawings, i. e., as a head and shoulder support, or as illustrated in Figure 3 from which it will be seen that the device is just as adaptable to use beneath any portion of the body and on the embalming board found desirable.

The device comprises an open frame composed of the side rails 2 and the cross or end rails 3. When used in the most common manner illustrated in Figure 1 the bottom cross rail 3 will be placed against any suitable edge or other abutment 4, so that when the lugs 5 with which the rails 2 are provided are properly engaged by the pivoted supporting arms 6, the device will be sup-

2
ported in the position shown for receiving the head, shoulders and upper portion of the body of the corpse.

While I have just described the usual positioning of the device for use it will be obvious that if the device could be used in that position only it would be useless in cases where abdominal or other body incisions than the usual one in the arm pit were necessary. To render my device universally adaptable I make it readily removably mountable and provide the side rails 2 with down turned end extensions 7 which serve to engage the embalming table for tilt-supporting the device in the effective manner illustrated in Figure 3 of the drawing.

By providing the open frame formed by the rails 2 and 3, either the upholstered cushion 8 or the drain pan 9 may be supported thereby. These two members, constructed as illustrated, are readily removable and interchangeable, the cushion being effective for ordinary supporting purposes and the drain pan combination being particularly effective during the actual embalming operation. The removable cushion feature is mentioned only as incidental to the invention and is illustrated in Figure 5 of the drawing.

30 The drain pan 9, which is preferably constructed of porcelain or enamelled metal, has a turned down or cupped end portion 10 which not only provides a neat appearance but fits down over the extended ends 7 and 35 serves effectively to prevent longitudinal displacement of the pan, and inverted U shaped side flanges 11 which snugly fit over the rails 2 to prevent lateral displacement of the said pan.

40 The main body or drain portion of the pan is depressed between the flanges 11 from the portion which engages the upper rail 3 to the portion which engages the lower rail 3, the depressed portion being inclined so as 45 to be about $\frac{1}{2}$ " to $\frac{3}{4}$ " deep at the upper end and about $1\frac{1}{4}$ " deep at the lower end. See Figures 1 and 2.

The lower end of the pan body terminates in an upwardly projecting back engaging 50 roll 12 adapted to engage the back of the corpse to prevent overflow or the trickling of fluid down the said back.

This inclined pan bottom is adapted to effect drainage of fluid received thereon into 55 the cross trough 13 formed adjacent the lower end of the pan by depressing the same about $\frac{1}{2}$ " or more. At one end of the trough 13, in one of the sides of the device, a discharge aperture 14 is provided through 60 which communication is had with the off-take drain tube 15, connected in the respective rail 2 and therewith as at 16, and through the said tube with the blood bottle or other receptacle.

65 When, in effecting the embalming opera-

tion, the body is positioned on my improved drain pan as described, all water used in washing, massaging and shampooing; all blood and other fluid exuding from the nose and mouth, is received and temporarily confined in the pan to be delivered through the tube 15 to the blood bottle or other receptacle without any attention from the embalmer or danger of inadvertant spilling.

In the usual operation the body is positioned so that the arm pit is over the pan adjacent the outlet 14. All that is then necessary is to raise the vein and open it. The blood will flow onto the drain pan, into the trough 13 and out through the outlet 14; without special attention by the embalmer; without the necessity of using drain tubes, rubber tube connections, arm pit drain pans, rubber floor sheeting or a host of other nuisances an embalmer commonly has to tolerate. The drain pan is thus very effective, practical and desirable; also neat of appearance, sanitary, and very convenient of use.

When an abdominal incision is necessary, as in cases of dropsy and leakage into that cavity, I place the device under the body at that point and make the incision as low down on the side as possible. The same manner of use is employed in cases of other body incisions. In this manner the device is universally effective.

From the foregoing description, taken in connection with the accompanying drawing, it is thought the novel details of construction, manner of operation and advantages, will be readily apparent to those skilled in the art to which it relates.

What I claim is:

1. A device of the class described comprising a frame, a drain pan removably mountable on the frame, said drain pan having flanges to fit the frame, an inclined and depressed drain body portion, a cross trough portion into which the drain body portion delivers, the said pan having a drain aperture at one end of said trough.

2. An embalmer's drain pan comprising a depressed and inclined drain body portion terminating at its upper end with a down-turned support portion and at its lower end with an upwardly projecting back engaging roll portion, and a cross trough portion into which the drain portion delivers, the said pan also having a drain aperture in communication with one end of the trough portion.

3. A device of the class described comprising a supporting frame composed of side and end rails, said side rails being extended and down turned at their upper ends, a drain pan removably mountable on the frame, the said pan having inverted U shaped side flanges for fitting over the side rails of the frame, an inclined and de-

pressed drain body portion terminating at its upper end with a downturned end and adapted to cup over the extended rail ends and at its lower end with an upwardly projecting back engaging roll portion, a cross trough portion into which the drain portion delivers, the said pan also having a drain aperture in one end of the trough portion, and take-off drain connections in communication with said drain aperture.

4. The combination with an embalmer's board having an abutment and a pair of supporting links, of a device of the class described comprising a frame adapted to rest against said abutment and having support lugs adapted to be engaged by said supporting links to support the device inclined to the horizontal, a drain pan removably mountable on the frame, said drain pan having flanges to fit the frame, an inclined and depressed drain body portion, a cross trough portion into which the drain body portion delivers, the said pan having a drain aperture at one end of said trough.

5. The combination with an embalmer's

board having an abutment and a pair of supporting links, of a device of the class described comprising a supporting frame composed of side and end rails, said side rails being extended and downturned at their upper ends, one of said end rails being adapted to rest against said abutment and said side rails having support lugs adapted to be engaged by said supporting links to support the device inclined to the horizontal, a drain pan removably mountable on the frame, the said pan having inverted U shaped side flanges for fitting over the side rails of the frame, an inclined and depressed drain body portion terminating at its upper end with a downturned end adapted to cup over the extended rail ends and at its lower end with an upwardly projecting back engaging roll portion, a cross trough portion into which the drain portion delivers, the said pan also having a drain aperture in one end of the trough portion, and take-off drain connections in communication with said drain aperture.

EPHRAIM R. JONES.
